WORK HOLDING FIXTURE AND POWER
MEANS FOR OPERATING THE SAMEAlan H. Pearson, Detroit, Mich., assignor to
Pearson Inc., Detroit, Mich., a corporation of
Michigan

Application May 10, 1950, Serial No. 161,101

4 Claims. (Cl. 81—17.2)

1

This invention relates generally to work holding fixtures and refers more particularly to improvements in fixtures of the type which automatically lock upon engaging the work to be clamped.

Fixtures of the above general type are used extensively in production, because of the rapidity with which they may be operated, and because of the rigidity with which they retain the work in position during machining or other operations. One objection to such fixtures is that they must be hand operated, and considerable time may be lost in production because of the necessity for the operator to free at least one hand for manipulation of the fixture.

With the above in view, it is an object of this invention to provide a work clamping fixture with means for automatically operating the fixture to both its clamping and released positions by merely touching a control which may be located in a position for convenient operation by one foot of the operator. However, even in instances where it is desired to operate the control by a hand of the operator, considerable time is saved over a long period of use, since it is only necessary for the operator to touch the control. Also operator fatigue is reduced to a minimum, and personal efficiency materially increased.

It is another feature of this invention to automatically operate the work clamping fixture with a power unit which is compact in construction and may be readily adapted to orthodox work clamping fixtures in a matter of minutes without materially altering the fixture.

The foregoing as well as other objects will be made more apparent as this description proceeds, especially when considered in connection with the accompanying drawings, wherein:

Figure 1 is a perspective view of a typical work clamping fixture having a power unit embodying the features of this invention attached thereto;

Figure 2 is a sectional view taken substantially on the line 2—2 of Figure 1;

Figure 3 is a cross sectional view taken on the line 3—3 of Figure 2;

Figure 4 is a cross sectional view taken on the line 4—4 of Figure 3; and

Figure 5 is a sectional view showing a slightly modified form of power unit.

The power units illustrated in Figures 1 to 5 50 inclusive are shown for the purpose of illustration as installed on a type of work holding fixture which has enjoyed practically universal acceptance by the trade for clamping work pieces in position during machining or other work per-

2

forming operations. Such fixtures ordinarily embody a quick acting lock for securely holding the work pieces against accidental movement during the work performing operation, and this lock is usually manipulated by a hand operated lever on the fixture. In accordance with the present invention, fixtures of the above general type may be quickly converted to automatic operation by merely removing the handle assembly, and attaching the power unit shown in Figures 1 to 4 inclusive of the drawings. The power unit featured in Figure 5 of the drawings incorporates the locking means as a part of its assembly, and has many diversified uses.

Referring first to the embodiment of the invention shown in Figures 1 to 4 inclusive, it will be noted that the reference numeral 10 in Figure 1 designates a typical work holding fixture, and the numeral 11 indicates a power unit for the fixture. The fixture selected herein for the purpose of illustration comprises a base 12 and a clamping plate 13 spaced vertically above the base 12. The base 12 has a work supporting surface 14 and a pair of laterally spaced vertical housings 15 extending upwardly from the base at one side of the surface 14. The clamping plate 13 has a pair of vertical shafts 16 respectively secured at the upper ends to the plate 13 by studs 17 and spaced laterally from each other in a manner such as to telescopically engage within the housings 15.

A driven shaft 18 extends perpendicular to the shafts 16 and is journaled in suitable bores formed in the vertical housings 15. The opposite end portions of the driven shaft respectively intersect the vertical path of travel of the shafts 16 and are formed with an annular series of teeth 19. The teeth 19, in effect, form pinions on the shaft 18 and respectively mesh with rack teeth 20 formed on the adjacent sides of the vertical shafts 16. The arrangement is such that rotation of the driven shaft 18 in a forward direction, or in the direction of the arrow 21, lowers the plate 13 into clamping position and rotation of the driven shaft 18 in the opposite or rearward direction raises the clamping plate 13 to its released position.

The clamping plate 13 is securely held in its clamping position by means of a locking device 22. The locking device 22 has a ring 23 concentrically positioned with respect to the driven shaft and removably secured to one side of the fixture 10 by studs 24. It will be noted from Figure 3 of the drawings that the adjacent end of the driven shaft 18 has a reduced portion 25 which

extends into the ring 23 and provides a support for a cam 26. The cam 26 is keyed to the driven shaft for rotation as a unit with the latter, and the periphery of the cam 26 is fashioned with three flats 27 spaced equal distances from each other circumferentially of the cam. It will be noted from Figure 4 of the drawings that the flats 27 cooperate with the inner surface of the ring 23 to form wedge-shaped spaces 28 and also provide shoulders 29. Suitable rollers 30 are respectively supported in the spaces 28 and these rollers are adapted to move into wedging engagement with the flats 27 and the inner surface of the ring 23 to effectively lock the clamping plate 13 in its clamping position. In other words when the rollers 30 are in their wedging position, rotation of the driven shaft 18 by the load in the reverse direction is prevented.

The rollers 30 are released from their wedging position to enable moving the clamping plate 13 to its inoperative position by a hub 31 supported at the front side of the ring 23 for rotation about the axis of the driven shaft 18. In accordance with conventional practice the hub is formed with three fingers 32 which project into the ring 23 and assume positions at the outer side of the cam 26 between the rollers 30. The arrangement is such that rotation of the hub 31 in a rearward direction engages the fingers with the rollers and shifts the latter out of wedging position. Thus the locking device 22 is released and the plate 13 may be returned to its released or inoperative position. On the other hand, rotation of the hub 31 in a forward direction imparts a thrust on the cam 26 tending to rotate the latter in a corresponding direction. As a result the rolls are released from their wedging positions, and the driven shaft 18 is rotated in the direction of the arrow 21 to move the plate 13 to its clamping position.

In conventional locking fixtures of the above general type, the hub 31 is attached to a hand operated lever. In the present instance, however, the hub 31 forms a part of the power unit 11, and is operated by the latter.

The power unit 11 comprises a housing 35 which may be in the form of a casting, and is fashioned with a casing 36 shown in Figure 3 of the drawings as aligned with the driven shaft 18. The inner end of the casing 36 has a cup-shaped portion 37 designed to receive the ring 23 of the locking device and is secured to the fixture 10 by the studs 24. The outer end of the casing is closed by a cap 38, and a fluid-tight joint is provided by a seal 39.

A drive shaft 40 is journalled within the casing 36 in axial alignment with the driven shaft 18, and the inner end of the shaft 40 is secured to a part 41 by a key 42. The part 41 is rotatably supported in the casing 36, and is secured or formed integral with the hub 31 for operating the latter. The arrangement is such that the locking device 22 serves as a unidirectional driving connection between the driving shaft 40 and the driven shaft 18. A suitable packing 43 is provided around the shaft 40 at the inner side of the part 41, and the seal 39 also has a part 44 which engages the outer end of the shaft 40 to prevent escape of fluid along the shaft from the interior of the casing 36.

The driving shaft 40 is rotated in opposite directions by a fluid motor, which is adapted for operation by either air or liquid under pressure. The fluid motor comprises a cylinder 45 and a double-acting piston slidably supported within

the cylinder. The cylinder 45 is formed on the housing 35 and extends at right angles to the casing 36. The ends of the cylinder 45 project laterally beyond opposite sides of the casing 36 at the outer end of the latter and the interior of the cylinder communicates with the interior of the casing 36 to enable projecting the shaft 40 across the cylinder.

One end 47 of the cylinder is reduced in diameter, and is closed by a cap 48 which is removably secured to the housing 35 by studs 49. The opposite or relatively large diameter end 50 of the cylinder 45 accommodates the piston 46, and is closed by a cap 51, which is removably secured to the housing by studs 52.

The housing 35 is fashioned with ports 53 and 54 respectively positioned to communicate with the interior of the cylinder adjacent opposite ends of the latter. As shown particularly in Figure 2 of the drawings, the ports 53 and 54 are alternatively connected by a four-way valve 55 to a fluid supply line 56 and to an exhaust line 57. The valve 55 may be operated by any suitable means (not shown) located at any selected point with respect to the fixture. As an example the valve 55 may be operated by a solenoid operated switch having a control positioned for convenient manipulation by one foot of the operator.

The piston 46 is of the balanced type, or in other words, is of a design which presents equal areas at opposite sides to the action of fluid under pressure. In detail the piston has a centrally apertured disc 58 clamped between a pair of heads 59 and 60. The head 60 extends through the central opening in the disc and is formed with an axially extending internally threaded bore 62. The head 59 has a stud 63 which threadably engages in the bore 62. A pair of opposed generally cup-shaped sealing elements 65 are provided on the piston to prevent escape of fluid under pressure past the piston when the latter is shifted in either direction in the cylinder.

Referring again to Figure 2 of the drawings, it will be noted that the head 60 has an axially projecting part 66 in the form of a shaft. The part 66 slides in the reduced portion 47 of the cylinder 45, and the top surface of the part is fashioned with a plurality of rack teeth 67. The teeth 67 are arranged in mesh with a pinion 68 formed integral with the adjacent portion of the shaft 40. It will also be noted that the part 66 has an axially extending passage 69, which extends from the free end of the part to the head 60 of the piston and opens into the cylinder at the adjacent side of the piston. The purpose of the passage is to facilitate the flow of fluid under pressure between the port 54 and the adjacent side of the piston 46.

Operation

Assuming that the valve 55 is in a position wherein the fluid pressure supply line 56 is connected to the port 53 and the exhaust line 57 is connected to the port 54, it will be noted that the piston 46 is moved from the position shown in Figure 2 toward the port 54. As a result the shaft 40 is rotated in the direction of the arrow 70 in Figure 2, and the hub 31 in Figure 3 is rotated in a corresponding direction. Thus the rollers 30 in the locking device 22 are released, and the driven shaft 18 is rotated in the direction of the arrow 21 in Figure 3 to move the plate 13 downwardly to its clamping position.

As soon as the plate 13 reaches its clamping position, rotation of the driven shaft 18 ceases,

and the rollers positively lock the shaft against reverse rotation by the reaction of the load on the clamp. Thus if for any reason the pressure of the fluid should drop or fail completely, the fixture is retained in its clamping position by the locking device 22, and danger of harming the operator, machine or tools is avoided.

When it is desired to release the clamp, the four-way valve 55 is operated to connect the port 54 to the fluid pressure supply line 56 and to connect the port 53 to the exhaust line 57. As a result the piston 46 is moved in a direction toward the port 53, and the drive shaft 40 is rotated by the rack part 66 in the reverse direction. Thus the hub 31 releases the rollers from wedging contact with the fixed ring 23 and permits reverse rotation of the driven shaft 18 to lift the clamping plate 13 to its inoperative position.

In accordance with this invention, the flow of fluid under pressure through the ports 53 and 54 may be independently varied by suitable metering pins 71 and 72. Thus the speed of operation of the clamp in either direction may be varied to suit different conditions, and the torque may be controlled, if desired.

The embodiment of the invention shown in Figure 5 of the drawings differs essentially from the above construction in that the locking device 22' is incorporated within the power unit 11. More particularly it will be noted that the casing 36 of the housing 35 is fashioned to accommodate the locking device 22'. The locking device 22' is essentially the same as the locking device 22, and corresponding parts are indicated by the same reference numerals. It may be pointed out that the ring 23 is secured against rotation relative to the casing 36 by a pin 76, and the hub 31 is secured against rotation relative to the shaft 40 by a pin 77. The cam 26 of the locking device is keyed to a driven shaft 78 which projects through a central opening formed in a closure cap 79 for the inner end of the casing. The shaft 78 may be coupled to the driven shaft 18 of the fixture 10, or may be coupled to any suitable device. In other words the embodiment of the invention shown in Figure 5 may be used for operating devices other than work holding clamps. In any case the operation of the power unit shown in Figure 5 is generally the same as the operation of the power unit shown in Figures 1 to 4 inclusive.

What I claim as my invention is:

1. A power unit for a work holding fixture having a clamping member supported for movement into and out of clamping position, said power unit comprising a fluid motor for moving the clamping member into and out of clamping position, said fluid motor having a cylinder, said cylinder having a portion at one end of reduced diameter, a double-acting piston slidably supported in the portion of said cylinder of greater diameter, a port in said cylinder adjacent one end thereof and a second port in said cylinder adjacent the opposite end, means for alternately supplying fluid under pressure to and exhausting the same from said ports to move said piston in opposite directions in said cylinder, a part slidably supported in the reduced portion of said cylinder and extending axially of the latter, said part being secured to the adjacent side of said piston for operation by the latter, a passage for fluid extending axially through said part and connecting the reduced portion of said cylinder to the relatively large diameter portion thereof at the side of said piston adjacent said reduced por-

tion, thereby to facilitate the flow of fluid under pressure between the relatively large diameter portion of said cylinder at the aforesaid side of said piston and the adjacent port, and means for operatively connecting said part to the clamping member for actuating the latter.

2. A power unit for a work holding fixture having a clamping member supported for movement into and out of clamping position, said power unit comprising a housing and a fluid motor in said housing for moving the clamping member into and out of clamping position, said fluid motor having a cylinder, said cylinder having a portion at one end of reduced diameter, a double-acting piston slidably supported in the portion of said cylinder of greater diameter, a port in said cylinder adjacent one end thereof and a second port in said cylinder adjacent the opposite end, means for alternately supplying fluid under pressure to and exhausting the same from said ports to move said piston in opposite directions in said cylinder, a drive shaft supported for rotation by said housing, a rack part slidably supported in the reduced portion of said cylinder and extending axially of the latter, said rack part being secured to the adjacent side of said piston for operation by the latter, a pinion within said cylinder secured to said drive shaft and meshing with said rack part for rotating said drive shaft in opposite directions upon movement of said piston in opposite directions, a driven shaft also supported for rotation in substantial alignment with said drive shaft, a unidirectional driving connection between said shafts including releasable means for locking said driven shaft against rotation in one direction, means operated by said drive shaft upon rotation thereof in said one direction to release said locking means and to impart rotation to said driven shaft in said one direction, and means for operatively connecting said driven shaft to the clamping member.

3. The structure set forth in claim 2 wherein said rack part has an axially extending passage therein connecting the reduced portion of said cylinder to the relatively large diameter portion thereof at the side of said piston adjacent said reduced portion, thereby to facilitate the flow of fluid under pressure between the relatively large diameter portion of said cylinder at the aforesaid side of said piston and the adjacent port.

4. A power unit for a work holding fixture having a clamping member supported for movement into and out of clamping position, said power unit comprising a housing and a fluid motor in said housing for moving the clamping member into and out of clamping position, said fluid motor having a cylinder, said cylinder having a portion at one end of reduced diameter, a double-acting piston slidably supported in the portion of said cylinder of greater diameter, a port in said cylinder adjacent one end thereof and a second port in said cylinder adjacent the opposite end, means for alternately supplying fluid under pressure to and exhausting the same from said ports to move said piston in opposite directions in said cylinder, a drive shaft supported for rotation by said housing, a rack part slidably supported in the reduced portion of said cylinder and extending axially of the latter, said rack part being secured to the adjacent side of said piston for operation by the latter, a passage for fluid extending axially through said rack part and connecting the reduced portion of said cylinder to the relatively large diameter portion thereof

thereof at the side of said piston adjacent said reduced portion, thereby to facilitate the flow of fluid under pressure between the relatively large diameter portion of said cylinder at the aforesaid side of said piston and the adjacent port, a pinion within said cylinder secured to said drive shaft and meshing with said rack part for rotating said drive shaft in opposite directions upon movement of said piston in opposite directions, and means for operatively connecting said drive shaft to said clamping member.
